No. 674,428.

Patented May 21, 1901.

P. PEARSON.

DRILL.

(Application filed Oct. 30, 1900.)

(No Model.)

UNITED STATES PATENT OFFICE.

PETER PEARSON, OF RICHHILL, MISSOURI.

DRILL.

SPECIFICATION forming part of Letters Patent No. 674,428, dated May 21, 1901.

Application filed October 30, 1900. Serial No. 34,933. (No model.)

To all whom it may concern:

Be it known that I, PETER PEARSON, a citizen of the United States, residing at Richhill, in the county of Bates and State of Missouri, have invented a new and useful Drill, of which the following is a specification.

This invention relates to improvements in drilling-machines; and the object is to provide a simple and improved construction of a drilling-machine which may be readily positioned for use in connection with coal or rock and quickly and readily operated.

With the above object in view the invention consists in the novel features of construction hereinafter fully described, particularly pointed out in the claims, and clearly illustrated by the accompanying drawings, in which—

Figure 1 is a perspective view of a drilling-machine embodying my invention; Fig. 2, a vertical longitudinal sectional view; Fig. 3, a detail view of one of the swinging supports for the short driving-shafts, and Fig. 4 a detail view of the boxing.

Referring now more particularly to the accompanying drawings, A designates a supporting-platform formed of four boards connected at their ends and forming a central space. Raised from the side boards of the platform adjacent to the central space are the two uprights B, braced by rods C. Pivoted to the upper ends of the uprights, so as to swing outwardly and downwardly therefrom, are arms D. Each of these arms supports a short driving-shaft E, carrying at its inner end a beveled gear F and at its outer end a disk G, having a handle H, by means of which the shaft may be rotated. The inner ends of these short driving-shafts terminate short of each other, so that the gears F are separated. Arms D are secured in alignment with the standards by set-screws I.

J designates one-half of a sectional boxing having laterally-extending plates K, which are secured to the standards B and support the boxing centrally between the standards. Hinged to one of the plates K is a swinging section L of the boxing, which is locked in position, forming, with section J, a complete boxing by means of pin M passing through an eye N, formed on section L, and eyes O, formed

on the opposite plate K. The boxing is provided adjacent to its upper end with an annular shoulder P and screw-threaded the remainder of its inner surface.

55

Q designates a beveled gear meshing with gears F, having a reduced portion R in the boxing and resting upon the annular shoulder P thereof. Said gear is formed with a centrally-disposed vertical passage to receive a screw-threaded tube S, which is movable therethrough, but held from independent rotation by a projection T, carried by the gear R and projecting into a longitudinally-extending slot U, formed in the tube S. The threads of this tube take the threads of the boxing, and as the gear Q is rotated said tube S is also rotated, and at the same time moved either upwardly or downwardly, according to the direction of rotation of the gear. Threaded on the lower end of tube S is a tubular bit V, formed on its lower end with saw-like cutting-teeth W.

By operating either one or both of the driving-shafts E the bit is rotated and at the same time fed downwardly and quickly and effectively drilling the coal or rock. By removing the set-screws I the arms supporting the driving-shafts may be swung outwardly out of gear. The spring-section L of the boxing may also be quickly and readily opened to permit the removal of the threaded tube S.

Tube S and bit V are provided with perforations X and Y, adjacent to their point of connection, to receive rods or any tool for the purpose of unscrewing or removing the bit.

Having thus fully described my invention, what I claim as new, and desire to secure by Letters Patent of the United States, is—

1. A drilling-machine comprising a supporting-frame, parallel standards raised therefrom, a screw-threaded boxing supported by and disposed between said standards, a gear rotatably supported by said boxing, a screw-threaded drill-holder movable through said boxing and through the gear supported thereby but held from rotation independently of said gear, arms pivoted at the upper ends of said standards, transversely-extending shafts supported by said arms carrying on their inner ends gears meshing with the gears supported by the boxing and on their outer ends

means for rotating them, and locking means for holding said arms in alinement with the standards, substantially as described.

2. A drilling-machine comprising a supporting-frame, parallel standards raised therefrom, a connecting portion between said standards at their upper ends formed with a centrally-disposed semicylindrical screw-threaded portion, a swinging section of the same form as said semicylindrical section, and screw-threaded and forming with said section a boxing, fastening means for securing said swinging section in operative position, swinging arms at the upper ends of the standards, transversely-extending shafts supported by said arms carrying on their inner ends beveled

gears and on their outer ends hand-wheels, means for locking said swinging arms in alinement with the standards, a gear rotatably supported by said boxing and having an inwardly-extending projection and meshing with said beveled gears of the shafts, and a screw-threaded drill-holder movable through said boxing and through the gear supported thereby, and formed with a longitudinally-extending groove receiving the projection of said gear, substantially as described. 25

PETER PEARSON.
